UNITED STATES PATENT OFFICE.

JOSEF MICHALIK, OF RONCO, PENNSYLVANIA.

COAL-LOADING APPARATUS.

Application filed July 22, 1924. Serial No. 727,539.

To all whom it may concern:

Be it known that I, JOSEF MICHALIK, a citizen of Poland, residing at Ronco, in the county of Fayette and State of Pennsylvania, have invented certain new and useful Improvements in Coal-Loading Apparatus, of which the following is a specification, reference being had to the accompanying drawings.

10 This invention relates to certain improvements in loading apparatus and has relation more particularly to a device of this general character especially designed and adapted for use in mines for loading coal and the like, and it is an object of the invention to provide an apparatus of this general character having novel and improved means whereby coal or kindred material may be readily conveyed in a pile to a car or the like.

25 Another object of the invention is to provide a novel and improved device of this general character comprising an endless conveyor moving in a suitable path of travel and which is provided with a plurality of shovels or blades normally maintained in a folded position against the conveyor but which are maintained in open or working position under the influence of the material carried by the conveyor.

30 Furthermore, it is an object of the invention to provide an apparatus of this kind embodying novel and improved means whereby the apparatus may be caused to move toward the pile of material to be loaded as the occasions of practice may require.

35 The invention consists in the details of construction and in the combination and arrangement of the several parts of my improved loading apparatus whereby certain important advantages are attained and the device rendered simpler, less expensive and otherwise more convenient and advantageous for use, as will be hereinafter more fully set forth.

40 The novel features of my invention will hereinafter be definitely claimed.

45 In order that my invention may be the better understood, I will now proceed to describe the same with reference to the accompanying drawings, wherein:

50 Figure 1 is a view in side elevation illustrating a loading apparatus constructed in accordance with an embodiment of my invention;

55 Figure 2 is a vertical sectional view taken longitudinally through the device as herein set forth;

60 Figure 3 is a view in top plan of the apparatus as herein disclosed;

65 Figure 4 is an enlarged fragmentary view partly in section and partly in elevation illustrating one of the blades or shovels in open position;

70 Figure 5 is an enlarged fragmentary view partly in section and partly in rear elevation of the structure as illustrated in Figure 4;

75 Figure 6 is a view in side elevation of one of the shovel or blade carrying links unapplied;

Figure 7 is a view in bottom plan of the link as illustrated in Figure 6;

80 Figure 8 is a view in perspective of one of the shovels or blades unapplied.

85 As disclosed in the accompanying drawings, T denotes a truck adapted to travel on the trackway R although I do not wish to be understood as limiting myself in this respect.

90 Mounted upon the truck T for lateral swinging movement, as indicated at 1, is a body B, said body comprising the side members 2 disposed downward and forward on a predetermined incline with the lower extremities connected by a bottom plate 3 adapted to have direct contact with the ground and to travel therealong. The upper rear portions of the side members 2 are provided with the rearwardly directed and horizontally disposed side members 4.

95 Rotatably supported by the upper and lower portions of the side members 2 and bridging the space therebetween are the shafts 5 and 6, said shafts each having fixed thereto inwardly of and adjacent to a side member 2 the sprocket 7. The outer end portions of the rear side members 4 having engaged therewith a shaft 8 having fixed thereto inwardly of and adjacent to each of the side members 4 a sprocket 9. Operatively engaged with each set of sprockets 7 and 9 is the upper stretch of a side chain 10 comprised in an endless conveyor, the lower stretch of each of said side chains being over an idler guide pulley 11 supported by the body B at proper position below an upper sprocket 7. The shaft 8 is supported for adjustment lengthwise of the side members 4 in order that the side chains 10 may be maintained taut, such adjustment of the shaft 8

being accomplished in any desired manner and preferably through the medium of a rod 12 having one end portion pivotally engaged, as at 14, with a sliding bearing 15 for an end portion of the shaft 8. The rod 12 is freely disposed through an outstanding bracket 16 carried by the adjacent side member 4 and threaded upon said rod 12 and contacting with the bracket 16 is the nut 17. By requisite loosening of each of the nuts 17 the side members or chains 10 may be loosened or tightened as the occasions of practice may necessitate.

At predetermined intervals each of the side chains has interposed therein a special link L provided in its side portions and at the opposite ends thereof with the recesses 18 in which the extremities of coacting links 19 are received and pivotally connected with resultant intervening webs 20 of the pins 21 and 21^a or the like. The pin 21 extends across the space between the side members or chains 10 and common to both of the transversely aligned links L.

Substantially defining the marginal portions of the side members 2 and 4 is an inwardly disposed trackway 22 provided along its under surface with a groove 23 and carried by each of the side members 2 and substantially bridging the space between the adjacent sprockets 7 is a lower trackway 24. The upper stretches of the side members or chains 10 travel between the upper portion of the trackway 22 and the trackway 24 resting upon the lower trackway 24 while each of the links L is provided with an outstanding rib or flange 25 which is received within the groove 23 whereby the side members or chains 10 are effectively maintained against displacement with respect to the trackways 22 and 24. Each of the links L has its body portion extending beyond the inner margin of each of the side members or chains 10 as is particularly illustrated in Figure 5.

Coacting with each of the pins 21 is a shovel or blade 26, one end portion of which being provided with a pair of downwardly disposed lugs 27 through which said pin 21 is freely disposed whereby the shovel or blade 26 is supported for swinging movement. The shovels or blades 26 are of a length to snugly fit between the side members 2 and are arranged uppermost with respect to the top stretches of the members or chains 10 with their free ends disposed upwardly or with said free ends of the blades or shovels 26 disposed forwardly and downwardly when comprised within the lower stretches of the side members or chains 10.

The upward or opening swinging movement of each of the shovels or blades 26 is limited by the outstanding lugs 28 carried by the opposite ends of the blade or shovel 26 and in close proximity forwardly or out-

wardly of the lugs 27, said lugs 28 contacting with the inwardly extending portions of the transversely aligned links L upon outward swinging movement of said blade or shovel.

Each of the blades or shovels 26 is normally maintained in a lowered or closed position and as herein disclosed this normal position is maintained by the coil springs 29 encircling the pin 21 below each of the inwardly disposed portions of the links L with one end portion of each of the springs in contact, as at 30, with said extended portion of the adjacent link and the opposite end portion of the spring, as at 31, contacting with an edge of the lug 27.

Also bridging the space between the side members 2 and suitably supported thereby is a wall or bottom 32 over which the material to be loaded is carried by the shovels or blades 26 in their upward movement, said wall or bottom 32 extending partially around, as at 33, the shaft 5 while the upper end portion extends, as at 34, a slight distance beyond the upper shaft 6 and delivers to a hopper 35 with which is adapted to be employed a chute (not shown) for properly delivering or discharging the material into a car or the like, said material being received within the hopper 35 as discharged from the adjacent portion 34 of the wall or bottom 32.

The upper shaft 6 exteriorly of a side member 2 has fixed thereto a sprocket 36 around which passes a chain 37 also operatively engaged with the shaft 38 in driven connection with the motor 39 carried by the base portion of the body B. By this means requisite rotation is imparted to the shaft 6 to effect the desired travel of the side chains or members 10.

The lower ends of the side members 2 are provided with the forward extensions 40 also connected by the plate 3. The forward ends of the extensions 40 at the upper portions thereof rotatably support therebetween a feed drum or roller 41 provided with the outstanding fingers 42. The roller or drum 41 is in driven connection through the chains 43 with the lower shaft 6, said connections coacting with the opposite end portions of said drum and shaft. As is particularly illustrated in Figure 1 each of said connections comprises a sprocket 44 secured to an extended portion of the shaft 5 and a sprocket 45 secured to a supporting trunnion or shaft 47 for the roller 41 and with which sprockets 44 and 45 the chain 43 is directly engaged.

The shaft 38 as herein disclosed is also disposed on each side of the body B and through which extended portion is fixed a drum 48 around which is adapted to be wrapped a cable 49. This cable 49 extends forwardly of the body and passes under a

guide pulley 50 carried adjacent to the forward end of the body and is adapted to be extended through and suitably secured to a jack or other stationary support arranged in advance of the apparatus.

As herein disclosed, when it is desired to cause the apparatus to move forwardly it is only necessary to impose sufficient pull upon the extended upper end portions of 10 each of the cables 49 to tighten the same on its drum 48 and as the shaft 38 rotates the desired forward travel of the apparatus will occur. When the apparatus has been advanced as desired the pull on the cable is released.

In practice, the drum or roller 41 rotates upwardly and rearwardly and as it enters the coal pile or the like throws such material upon the forward portion of the plate 3 and 20 upon the shovels or blades 26 which begin to pass upwardly and over the lower shaft 5. The weight of the material received by each of the shovels or blades 26 will serve to hold the same in its raised or working position as illustrated in Figure 2, and such position of the shovel or blade will be maintained until the load carried thereby is deposited within the hopper 35 whereby the blade or shovel 26 will be automatically 30 turned to its closed or inoperative position. This latter or normal position of the blades or shovels 26 is required in order that no hinderance or obstruction will be offered by any of the parts of the apparatus to the 35 requisite travel of the conveyor.

Associated with the side members 2 are the side boards 51 detachably held in applied position, as at 52.

The wheels 53 of the truck T are mounted 40 on the axles 54, said axles being in driving connection one with the other through the medium of the chain 55 coating with the sprockets 56 carried by the axles 54. One of the axles 54 is in driven connection through 45 the chain 57 with the shaft 38 such connection being under control of the clutch mechanism 58 so that such driving connection as afforded by the chain 57 may be rendered operative or inoperative as desired. By this 50 means the device in its entirety may be driven along the trackway R from the motor 39.

Interposed between the lower portion of each of the side members 2 and the adjacent 55 end of the truck T is a jack 59 whereby the lower end portion of the apparatus may be readily elevated above the ground so that no hinderance will be offered thereby when it is desired to transport the apparatus in 60 its entirety.

I also find it of advantage to provide means for holding the body B against rotary movement around its axis 1 and especially when the apparatus is transported 65 and as herein disclosed this is accomplished

through the medium of a clamp 60 coating with the adjacent side portions of the body B and the truck T.

If desired, each of the cables 49 may be engaged with the wheels or rollers 61 carried by the rear portion of the body B.

From the foregoing description it is thought to be obvious that a loading apparatus constructed in accordance with my invention is particularly well adapted for 70 use by reason of the convenience and facility with which it may be assembled and operated, and it will also be obvious that my invention is susceptible of some change and modification without departing from the 75 principles and spirit thereof and for this reason I do not wish to be understood as limiting myself to the precise arrangement and formation of the several parts herein shown in carrying out my invention in practice except as hereinafter claimed.

I claim:

1. A loading apparatus comprising a body structure, an endless conveyor carried thereby, means for driving said conveyor, said conveyor consisting of side members, shovels pivotally supported by said side members, said shovels having movement toward and from the side members, and means for normally maintaining said shovels at the limit of their movement toward the side members.

2. A loading apparatus comprising a body structure, an endless conveyor carried thereby, means for driving said conveyor, said conveyor consisting of side members, shovels pivotally supported by said side members, said shovels having movement toward and from the side members, means for normally maintaining said shovels at the limit of their movement toward the side members, and means for limiting the movement of the shovels in the opposite direction.

3. A loading apparatus comprising, in combination, a body provided with inclined side members, the opposed faces of the side members being provided with a trackway, side members travelling within the trackway, said side members including links, shovels pivotally connected with said links and substantially bridging the space between the side members, said shovels having swinging movement toward and from the side members, and means for constantly urging said shovels toward the side members.

4. A loading apparatus comprising, in combination, a body provided with inclined side members, the opposed faces of the side members being provided with a trackway, side members travelling within the trackway, said side members including links, shovels pivotally connected with said links and substantially bridging the space be-

tween the side members, said shovels having swinging movement toward and from the side members, means for constantly urging said shovels toward the side members, the links by which the shovels are supported and the trackway being provided with coacting means for holding said side members within the trackway.

5. A loading apparatus comprising, in combination, a body provided with inclined side members, the opposed faces of the side members being provided with a trackway, side members travelling within the trackway, said side members including links, shovels pivotally connected with said links and substantially bridging the space between the side members, said shovels having swinging movement toward and from the side members, means for constantly urging said shovels toward the side members, the links by which the shovels are

supported and the trackway being provided with coacting means for holding said side members within the trackway, and means carried by the shovels and coacting with said links for limiting the swinging movement of the shovels in the opposite direction. 25

6. A loading apparatus comprising a body structure, an endless conveyor carried thereby, means for driving said conveyor, said conveyor consisting of side members, shovels pivotally supported by said side members, said shovels having movement toward and from the side members, means for normally maintaining said shovels at the limit of their movement toward the side members, said body being portable, and means for moving the same. 30

In testimony whereof I hereunto affix my 35 signature.

JOSEF MICHALIK.
